US00D825603S

(12) **United States Design Patent** (10) Patent No.: **US D825,603 S**
(45) Date of Patent: **** Aug. 14, 2018**

(54) **DISPLAY SCREEN OR PORTION THEREOF
WITH GRAPHICAL USER INTERFACE**

(71) Applicant: **SAP SE**, Walldorf (DE)

(72) Inventors: **Florian Jann**, Heidelberg (DE);
Michael Krenkler, Wiesloch (DE);
Emil Voutta, Heidelberg (DE); **Marc Ziegler**, Mauer (DE)

(73) Assignee: **SAP SE**, Walldorf (DE)

(**) Term: **15 Years**

(21) Appl. No.: **29/613,176**

(22) Filed: **Aug. 8, 2017**

Related U.S. Application Data

(63) Continuation of application No. 29/539,986, filed on Sep. 18, 2015.

(51) **LOC (11) Cl.** **14-04**

(52) **U.S. Cl.**

USPC **D14/486**

(57) **CLAIM**

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is a front view of a second embodiment thereof. The outermost broken lines in the figures show a display screen or portion thereof, and form no part of the claimed design. The other broken lines in the figures show portions of the graphical user interface that form no part of the claimed design.

1 Claim, 2 Drawing Sheets
